Primary Examiner — Messina L Smith*Assistant Examiner* — Jillian Mazzola(74) Attorney, Agent, or Firm — Rothwell, Figg, Ernst & Manbeck, P.C.(57) CLAIM

The ornamental design for a bag, as shown and described.

DESCRIPTION

FIG. 1 is a perspective view of a bag, showing my new design;

FIG. 2 is a front view thereof;

FIG. 3 is a rear view thereof;

FIG. 4 is a left side view thereof;

FIG. 5 is a right side view thereof, opposite that of FIG. 4; and,

FIG. 6 is a top view thereof.

The V trademark, shown in FIGS. 1 and 2 of the claimed design, is a registered trademark of (REGISTRANT) VALENTINO S.P.A. JOINT STOCK COMPANY ITALY Via Turati 16/18 I-20121 Milano ITALY.

The broken lines shown in the figures depict portions of the bag that form no part of the claimed design.

1 Claim, 6 Drawing Sheets(56)
